Claims priority, application Japan Nov. 26, 1971

Term of patent 14 years

Int. Cl. D7—02

U.S. Cl. D7—93

FIG. 1

FIG. 3

FIG. 2

FIG. 4

FIG. 5

FIG. 6

FIG. 7

FIG. 9

FIG. 8

FIG. 10

FIG. 11

FIG. 12

FIG. 1 is a right side elevational view of a toaster showing our new design according to a first embodiment thereof;

FIG. 2 is a left side elevational view;

FIG. 3 is a top plan view;

FIG. 4 is a bottom plan view;

FIG. 5 is a front elevational view;

FIG. 6 is a front and right side perspective view thereof;

FIG. 7 is a right side elevational view of a toaster showing our new design according to a second embodiment thereof;

FIG. 8 is a left side elevational view;

FIG. 9 is a top plan view;

FIG. 10 is a bottom plan view;

FIG. 11 is a front elevational view; and

FIG. 12 is a front and right side perspective view thereof.

The rear elevational views are mirror images of the front elevational views respectively.

This is a division of design application Serial No. 255,950 filed May 22, 1972.

We claim:

The ornamental design for a toaster, as shown and described.
